STRIP COILING MACHINE

Erik W. Mikaelson, Easton, Pa., and Alexander K. Hamilton, Chicago, Ill., assignors to Treadwell Engineering Company, Easton, Pa., a corporation of Pennsylvania

Application January 23, 1934, Serial No. 707,980

8 Claims. (Cl. 153—54)

This invention relates to mechanism for coiling strip.

Sheet metal in strip form is now produced in large quantities and is supplied to manufacturers of various types of articles for further fabrication. The finished strip or narrow sheet is the product of rolling operations in which a billet of considerable size is converted into the form of a thin relatively narrow strip of comparatively great length. In nearly all cases the strip, as it comes from the rolling mill, is too long to permit its handling or shipment when it is in extended condition, and hence it is customary to provide, in conjunction with mills for rolling strip of this nature, coiling machines which receive freshly rolled strip as they come successively from the mill and form them into coils, each strip being formed into a separate coil. Where the coiler is positioned in close proximity to a mill rolling hot materials, a water spraying device may be located between the two and a sufficient amount of water sprayed onto the strip passing from the mill to lower its temperature to such extent that it will retain its bend after passing the guide leading to the coil carrying rolls of the coiler. In its coiled condition the strip may be readily handled, packed for transportation, and transported to the point at which it is to be ultimately fabricated into metal articles, or it may be subjected to the action of a pickling bath to remove scale and then subjected to further rolling operations. The present invention relates particularly to a strip coiling mechanism of the class just described, and it is the general object of the invention to provide a strip coiling machine of improved type and having a number of novel features which render it superior in operation to all coiling machines heretofore designed, suggested, or put into operation.

The invention contemplates an improved strip bending mechanism, that is, an improved mechanism for continuously bending or curving the strip just prior to the actual formation of the coil. By its use the operator of the machine is enabled to bend with equal facility, and to the exact degree desired, strips which vary in thickness, chemical composition, and elastic limit, the bending apparatus being susceptible of adjustment in a novel manner with this end in view. It will be appreciated that it may be quite necessary, in placing the desired permanent curvature in a strip having certain chemical and physical characteristics, to cause the bending mechanism itself to act upon such a strip in

a manner quite different from the manner in which the same bending mechanism must be caused to act upon a strip of different thickness and physical and chemical characteristics.

Coiling machines of previously known type have been capable of coiling strip varying in physical and chemical characteristics but, by reason of the design and arrangement of the bending rolls of such machines, great difficulties have been met with in actual operation. Thus, in the case of the coiling machine heretofore most commonly used, certain relative adjustments of the bending rolls to impart the desired curvature to strip having certain physical and chemical characteristics have brought them into such relationship that proper entry of the leading edge of a rapidly oncoming strip between the bending rolls has very frequently not been realized, with resulting injury to the machine and destruction of valuable strip. This difficulty has been particularly acute in those cases in which coiling machines have been located in rather close proximity to rolling mills as, in such a case, the leading edge of a strip may reach the coiling machine while a subsequent portion is still passing through the rolling mill and is therefore being advanced at the relatively high rolling mill velocity.

In accordance with this invention, a bending apparatus is provided which is readily adaptable in this respect, and with slight loss of time its operator may effect all adjustments necessary to convert the machine from one having a bending mechanism particularly arranged for the bending of one kind of strip, into a bending mechanism particularly adapted for the satisfactory and efficient bending of an entirely different kind of strip, the machine permitting free entry of the leading edge of a strip for all possible relative adjustments of its rolls.

The invention further contemplates an improved coil receiving and supporting means. As the strip emerges from the bending apparatus with the desired curvature therein, it passes into a space in which it actually forms itself into a coil. Several important improvements have been made in the coil forming mechanism whereby the operator has greater control over the coiling operation and a better product is insured. The means for laterally guiding and supporting the coil and the incoming curved strip particularly has been improved so that coils of large diameter and formed from relatively narrow strips can be easily built up.

In accordance with this invention also, the

mechanism for feeding the oncoming strips along a predetermined path to the strip bending means is improved. This mechanism includes in the usual machine of this character plate supporting 5 and guiding means, a device for downwardly deflecting upon this means the upwardly curved leading edge of an oncoming strip, and pinch rolls for gripping the blank after it is passed over such guiding means and positively feeding 10 the same through the bending mechanism and thence to the coiling space. In accordance with our present invention, improvements have been made in the guide, in the pinch rolls, and in the deflecting means whereby these several parts are 15 caused to function more efficiently and satisfactorily than heretofore.

Many other improvements to various parts of the machine are contemplated by the invention, and in particular novel mountings for the 20 various strip engaging rollers have been provided whereby the rollers are satisfactorily supported against end thrust during operation of the machine but at the same time are readily removable so that they may be individually removed when- 25 ever necessary or desirable and without disturbing or dismantling any portions of the machine except the roll mountings.

In the accompanying drawings a strip coiling machine is illustrated, and in this machine are 30 incorporated the various features of our invention. It is, of course, true that these features of novelty may be included in strip coiling machines which differ widely in appearance from that which is set forth in the drawings by way of example and that, in adapting the inventions to coiling machines of different design and type, the various component elements of the invention may be considerably modified as to design and arrangement without departing from the invention 40 in substance.

In the drawings:

Figure 1 is a plan view of the strip coiling mechanism selected for disclosure by way of example;

Figure 2 is a side view of the same, partially 45 shown in elevation and partially shown in section;

Figure 3 is an end elevation of the machine;

Figure 4 is a section on line 4—4 of Figure 1;

Figure 5 is a section on line 5—5 of Figure 2;

Figure 6 is a section on line 6—6 of Figure 5;

Figure 7 is a section on line 7—7 of Figure 5;

Figure 8 shows a detail;

Figure 9 is a section on line 8—9 of Figure 4;

Figure 10 is a diagrammatic view showing the 55 usual relative positioning of the three bending rolls of a coiling machine of the prior art; and

Figures 11 and 12 indicate diagrammatically two possible positions of relative adjustment of the bending rolls of the improved coiling machine.

60 While the frame of the machine may be formed in various ways, it may conveniently be constructed as shown in the drawings, having spaced vertically disposed and generally parallel supporting pedestals 10 and 11, upon the upper surfaces of 65 which is mounted the horizontally extending cap portion 12. The cap 12 may be a one-piece casting or may be formed of several smaller members secured together as by bolting. The strip bending mechanism comprises three rolls, the upper 70 roll A and the lower rolls B and C, the strip S which is being fed into the machine to be coiled passing between the upper roll A and the lower rolls B and C, as shown in Figure 4 and in Figures 75 10-12 inclusive, and the desired curvature being imparted to the strip as it passes through this

mechanism. To the right of the bending rolls, Figure 4, is the feed mechanism including the pinch rolls D and E which frictionally grip the strip between them to feed the same through the bending mechanism. Located just above the 5 bending mechanism is the coil carrying mechanism, and in Figure 4 of the drawings the leading edge of blank S is shown to be coiled, this leading edge forming the innermost convolution of the coil which may be subsequently built up into a 10 relatively large annulus, having an outside diameter dependent upon the length of the strip from which it is formed. The completed coil is discharged from the coil carrying space by a suitable mechanism immediately after the coiling operation is concluded, thus clearing the machine 15 for a further coiling operation.

Strips freshly produced by rolling operations 20 pass into the strip feeding means of the coiling machine, being advanced along horizontal trackways to the machine by mechanisms not shown, and move into the coiler in the direction of the arrow T, Figures 1 and 4. The machine itself has a portion 13 which acts as a strip supporting 25 and guiding member, this member 13 being in effect a continuation of any desired type of strip conveyor. After the leading edge of a strip passes over the member 13 and over a hinged continuation 14 thereof, it enters between and is engaged by pinch rolls D and E which are positively driven 30 at the desired speed and act to feed the strip forwardly over an intermediate guide 15 to the bending rolls A, B, and C previously referred to. The pinch rolls are relatively adjustable, the upper pinch roll D (Figure 7) having its reduced ends 35 carried in rectangular blocks 16 and 17 suitably fastened to the cap 12 of the frame or housing. The upper pinch roll is therefore fixed in position. The ends of the lower pinch roll E are rotatably mounted in rectangular blocks 18 and 19 carried 40 by a pinch roll supporting frame 20 extending transversely of the machine.

Frame 20 has projections 20' at its ends, which 45 projections are, respectively, provided with approximately hemispherical recesses underneath, each of which receives the rounded upper end of a short strut 21. The lower ends of struts 21 are similarly rounded and are received within spherical recesses formed in the upper sides of levers 22 respectively, one end of each of these levers 50 being fixed on cross shaft 23 so that the levers are constrained to act in unison in their rocking movements about the axis of shaft 23. Positioned beneath one or both of levers 22 is a power cylinder, these cylinders being indicated at 24 and the pistons therein being indicated in dotted lines at 25 in Figures 3 and 5. Extending between each piston 25 and the lever 22 located above the same is an adjustable pitman 26, the ends of each such pitman being rounded. A 55 plurality of spherical recesses 22' are formed upon the lower sides of levers 22, and the upper ends of the pitman may be adjusted from one pair of recesses 22' to another with the result of increasing or decreasing as desired, within limits, the mechanical advantage obtained by the use of levers 22 in lifting the lower pinch roll by means of the pressure cylinders. Adjustable stops 27 of any suitable type are provided for ultimately limiting the upward movements of levers 22 under 60 the influence of the pressure cylinders and hence limiting the upward travel of the lower pinch roll.

The means for supplying the pressure cylinders 65 24 with fluid or gas under pressure is not illustrated, but it will be understood that any suitable 70

means may be employed to simultaneously introduce fluid under the pistons 25 and to simultaneously exhaust the fluid from under the pistons. By varying the fluid pressure and adjusting the position of the pitman 26, it is possible to vary as desired the pressure of the lower pinch roll upon a strip passing between it and the upper pinch roll. In its rising and falling movements, the pinch roll and the carrying frame 20 effect vertical movement of the adjacent portion of the strip supporting guide, the bracket-like supporting plate 15 previously referred to being rigidly mounted upon frame 20 and the free end of the hinged section 14 of the supporting guide being supported by frame 20. When the pinch roll E is lowered, therefore, the adjacent guide portions will be lowered, and hence the strip S may pass freely between the pinch rolls while at the same time it is adequately supported.

Occasionally a strip may be delivered from the rolling mill with its leading edge upwardly deflected, as indicated in dotted lines at S' in Figure 4, and for the purpose of guiding this edge downwardly in a sure and positive manner an upper guide is provided which comprises a movable part 30 and a stationary part 31. The movable part includes a plurality of belts or sprocket chains 32, each chain being endless and passing around pairs of spaced sprockets 33 fixed upon shafts 34 and 34', respectively. The lower reach of each sprocket chain is downwardly and forwardly inclined, and shaft 34' is positively driven in the direction of the arrow V and at a sufficiently high angular velocity to insure that the lower reach of each chain moves in the direction of the pinch rolls at a linear speed higher than the speed of advancement of the leading edge of the strip S'. The driving means for shaft 34' is shown in Figure 1 and is seen to comprise a chain and sprocket connection 36 to an extension of the upper pinch roll. Any suitable means may, of course, be employed to drive the chains 32. The stationary member 31, previously referred to, comprises a series of fingers lying between chains 32 which serve to guide the strip in passing from the chains to the pinch rolls.

After passing between the bending rolls, by means of which the strip is given a permanent curvature in a manner hereinafter to be more fully explained, it passes upwardly into the coiling space, and to insure that it shall pass upwardly in the desired manner, as shown in Figure 4, a curved guide is provided, this guide comprising a transverse member 40 supported upon the lower ends of curved arms 41, the upper ends of these arms being fixed on cross shaft 42 supported in bearings on the frame. Integral with transverse guide member 40 and projecting downwardly therefrom are the curved guide fingers 43, the lower ends or tips of which terminate just short of the roll B when the arms 41 are in the positions illustrated in Figure 4, that is, while the initial convolutions of the coil are being formed. A coil delivery platform is indicated at 44, and this platform is provided with notches or recesses 44' to permit free passage of fingers 43 as the arms 41 move upwardly and downwardly. Also mounted upon arms 41 are the coil guiding rolls 45 and 46. A further coil guiding roll is indicated at 47, this roll being mounted upon a horizontally reciprocable coil discharging head 48. Head 48 is slidable in the frame and has an actuating rod 49 connected to a piston 50 in a cylinder 51.

Means (not illustrated) is provided for sup-

plying fluid under pressure to the opposite ends of the cylinder to effect reciprocation of the piston as desired and movements of the head 48. Also rotatably mounted in the frame are two lower coil carrying rolls 52 and 52' which bear the weight of the coil during the time that it is held within the coiling machine. As the diameter of the coil increases, it tends to raise arms 41, acting first through roll 45 and then through roll 46. It is the primary function of the structure comprising arms 41 and rolls 45 and 46 to prevent the coil from falling or jumping out of the coiling space, due to possible unevenness and high speed of rotation. As the coil approaches maximum diameter, it is also guided by roll 47 in its rotational movement.

The weight of rolls 45 and 46 together with arms 41 and the guide affixed to the lower end of these arms is, in the average case, carried by the coil, and if desired the pressure upon the coil can be increased by the action of fluid pressure upon piston 55 in cylinder 56. Cylinder 51 is supported by the frame, and piston 50 is provided with a piston rod 57 projecting through the end of the cylinder and connected by a pin and slot connection with an arm 58 also fixed on cross shaft 42. Means (not illustrated) is provided for introducing fluid under pressure into the cylinder upon either side of the piston and for simultaneously exhausting the opposite end of the cylinder. By this mechanism the guide rolls 45 and 46 may be caused to bear upon the coil in process of formation with greater or less pressure as desired, in some instances it being considered advisable to increase the pressure upon the coil and in other instances to substantially relieve it. The power means just described also is called into operation when it is desired to lift the arms 41 to clear the completed coil prior to the actuation of the head 48 to push this coil out of the coil forming space 40 and onto the inclined platform 44 down which it rolls to suitable receiving apparatus.

During the formation of the coil, it is highly desirable that it be confined laterally on the carrying rolls, particularly where coils are being formed from relatively narrow strips. In order to thus laterally confine the coil, we provide lateral guiding discs 65 and 66. These discs are similarly formed and mounted. Each is fixed upon the end of a short shaft 67 rotatably mounted in bearings supported upon a pedestal 68 which is in turn slidably supported upon the top of the cap 12 of the frame or housing. Each pedestal 68 also supports a casing 69 which encloses and supports reduction gearing, indicated generally at 70, and a variable speed electric motor 71 provided for the purpose of driving shaft 67 and hence disc 65 at any desired angular velocity. Pedestal 68 may be moved toward the coiling space or away from the same by any suitable mechanism, as for instance by means of the threaded shaft 72 which projects through an interiorly threaded aperture formed in the downward extension 68' of the pedestal. A hand wheel 73 is provided for rotating shaft 72, but power means such as an electric motor may be provided if desired. It will be observed from an inspection of Figures 1 and 2 that the shafts upon which the discs 65 and 66 are mounted are disposed at slight and similar angles to the path of movement of a strip through the machine and that the inner guiding faces of discs 65 and 66 are not parallel but, on the other hand, diverge outwardly. The guiding faces of the discs are, however, vertically disposed at all times.

During the formation of a coil, the discs 55 and 66 are spaced apart a sufficient distance to provide a clearance between each disc and the nearest portion of the coil. As the coil approaches maximum diameter, so that its central axis approaches the axes of rotation of the discs, the discs may be rotated in the direction that the coil is being revolved and at such angular velocity that its speed at its point of contact with the strip is approximately the same as the speed of the strip, thus comprising rotating guides for the coil. By reason of the divergence of the guiding faces of the discs, it is an easy matter to eject the coil from the coiling space after it has been completely formed.

Again referring to the strip bending mechanism which includes as its principal elements the bending rolls A, B, and C, it will be seen from an inspection of Figures 3, 5, and 6 that the upper roll 20 A is a fixed roll, its ends being rigidly mounted in the top or cap portion 12 of the housing. The lower rolls B and C are, however, both adjustable, the ends of rolls B being rotatably supported in chucks 80 which are in turn supported adjustably 25 in the frame members 10 and 11, the ends of roll C being also mounted in adjustably supported chucks 81. The chucks 80 and 81 on opposite sides of the machine may be identical, and each pair of chucks is housed within a substantially 30 rectangular aperture 82 formed in members 10 and 11, guide plates such as 83 being provided on opposite sides of each such aperture to laterally confine the chucks while permitting adjustment thereof in the plane of the frame member. 35 Chuck 81 is supported upon the upper end of a threaded shaft 84, which shaft is prevented from rotation by means of a key 85 supported in a stationary sleeve 86 and projecting into a keyway in the shaft. It may be raised or lowered, however, 40 by means of an interiorly threaded nut 87 positioned below the stationary sleeve and rotatably carried by the frame. Nut 87 is provided with external worm teeth 88 which mesh with the teeth of a worm 89 fixed upon shaft 90 extending 45 transversely of the machine and having a hand wheel 91 fixed on its outer end. By rotating the hand wheel 91, the nut 87 may be revolved and the threaded vertical shaft 84, with its superposed chuck 81, may be raised or lowered as desired. 50 The weight of chuck 80 is carried by a similar vertically disposed threaded shaft 84', which shaft also has threaded engagement with a nut 87' similar to the nut 87 and also rotatably supported by the frame, nut 87' having external 55 worm teeth 92 which likewise mesh with the teeth of worm 89. Rotation of shaft 90 therefore effects not only the rotation of nut 87 but also of nut 87' and the simultaneous raising or lowering of threaded shafts 84 and 84' together 60 with the chucks 80 and 81 which they respectively support. Superposed upon nut 87' is a third sleeve 93 provided with a key 94 which projects within a keyway formed in the shaft 84', the cylindrical interior surface of sleeve 93 65 not being threaded, however, and there being a clearance between this surface and the threads formed exteriorly upon the shaft 84'. Sleeve 93 is provided with external worm teeth 95 which mesh with the teeth of a worm 96 fixed on shaft 97, to the end of which is fastened a hand wheel 98. Rotation of hand wheel 98, therefore, causes 70 rotation of sleeve 93 and axial movement of shaft 84' by reason of the fact that shaft 84' has threaded engagement with the lower nut 87', 75 which nut is locked against rotation, so far as

the operation of worm 96 is concerned, by means of worm 89. Rotation of hand wheel 98, therefore, will effect raising and lowering of chuck 80 and bending roll B alone, while rotation of shaft 90 while shaft 97 is stationary will effect simultaneous upward or downward movement as desired of both chucks 80 and 81 and bending rolls B and C. It will be understood that shafts 90 and 97 extend transversely of the machine from frame member 10 to frame member 11 and 10 that similar chuck raising and lowering mechanisms are positioned in both of these frame members so that, by the rotation of hand wheels 91 or 98, the rolls B and C might be simultaneously elevated or depressed, or the roll B elevated 15 or depressed by itself, the axes of these rolls being at all times in parallel relationship to the axis of roll A.

By referring to Figure 9, the mechanism for simultaneously or individually adjusting the rolls 20 bodily in a vertical direction may be more clearly understood, shafts 90 and 97 being completely illustrated. From this illustration it may be perceived also that it is possible to vertically adjust one end of each roll with respect to the other 25 end of the same roll. Thus the worms 89 and 96 to the left (Figure 9) are loose on shafts 90 and 97 and are connected to these shafts through detachable coupling members 89' and 96'. By removing the bolts which secure coupling member 89', for instance, the angular relationship of the shaft 90 and the left-hand worm may be changed as desired by rotating the shaft 90. After the adjustment of roll C has been effected, the coupling 89' may again be bolted in position, thus completing the adjustment. During the rotation of shaft 90 in effecting the adjustment of roll C, adjustment of screw 84' in housing 11 is also brought about, thus causing movement of one end of roll B with respect to the other. To 40 readjust this roll B to original position, coupling 96' is disconnected from shaft 97 and the adjustment carried out as in the case of roll C. Naturally rotation of shaft 90 with one worm disconnected effects vertical movement of the 45 right-hand end of roll C while the left-hand end remains stationary. The same method of adjustment may be carried out with respect to the roll B whenever necessary.

The chucks 80 and 81 merely rest upon the upper ends of threaded shafts 84' and 84, not being affixed thereto, and are adjustable horizontally as well as vertically in the recess 82. In addition to the chucks 80 and 81, the recess 51 includes the liners 100, 101, and 102. The space 52 between the vertical side walls of the recess 82 is completely filled by the chucks and the liners taken together and, should there be any slight looseness, it is taken up by means of the pressure screws 103 which pass through the frame member and bear against the surfaces of chucks 80. Each of the liners is removable and replaceable by a liner of different thickness, and by properly selecting liners of the desired thickness, the axes of rolls B and C may be horizontally 6 adjusted as desired, within limits. Thus, by increasing the thickness of liner 101, the axes of these rolls may be moved farther apart, and by decreasing the thickness of this liner, that is, by substituting a thinner liner, the axes of these rolls may be caused to approach each other. Naturally the substitution of one liner 101 for another of different thickness at this position will require the substitution for either liner 100 or 102 of a thicker or thinner liner as the case may be.

In a similar manner the liner 102 may be removed and one of a different thickness inserted. If a thinner liner is inserted, the axis of roll C will be moved to the right (Figure 5) while if a thicker liner is inserted, it will be moved to the left. Similarly, by the manipulation of the liners, the axis of roll B may be moved to the right or to the left as desired. Upon the chuck 80 is adjustably supported a small shoe or intermediate guide 104 for guiding the leading edge 10 of a blank so as to pass over roll B after having passed roll C, guide 104, of course, extending from one side of the machine to the other.

By the mechanism just described it is possible to adjust the relative positions of the rolls with facility in order to procure the sought-after bending effect upon the work passing through and to attain the necessary parallelism of the rolls A, B, and C. The bending rolls B and C may be relatively adjusted either vertically or horizontally. They may be simultaneously adjusted vertically by the simple operation of the hand wheel 91. Roll B may be adjusted vertically independently of roll C by manipulating the hand wheel 98. In other words, by the mechanism just described the operator is enabled to adjust the positions of rolls B and C relatively to each other and to the roll A in any desired manner, within the limits of the machine, to produce the proper bending effect upon the strip passing through. This is a function highly important to the operation of the machine. It will be understood, however, that while we have disclosed one eminently satisfactory mechanism for the relative adjustment of the rolls in the specified manner, other mechanisms for accomplishing this object can be readily substituted therefor. Wedges might be employed, for instance, to effect horizontal adjustment of the chucks and the rolls supported thereby or other mechanical means chosen for this purpose. It is quite possible to use power operated means for effecting the adjustment, if such adjustments are to be frequently made.

The pinch rolls and the bending rolls are positively driven by a suitable power means at the desired angular velocities. The driving motor is preferably an electric motor and is indicated at 110 in Figure 1, this motor being connected through conventional reduction gearing housed in a casing 111 and through spindles 112 to couplings 113 detachably mounted upon the ends of the several rolls respectively. As may be seen from an inspection of Figures 6, 7, and 8 and other figures of the drawings, the reduced end portions of each roll are directly supported in lining members. The carrier rolls 52 and 52' are readily removable from the frame. In Figure 6 one of these rolls is shown, its reduced left-hand end portion being mounted in a lining member 114 supported by the frame, and its reduced right-hand end portion being supported in a liner 115 which is in turn carried by a sleeve 116 mounted in the frame. The outer diameter of sleeve 116 is greater than the outer diameter of the main portion of the carrier roll, and hence, after removal of sleeve 116 and liner 115, the roll may be withdrawn through the right-hand cylindrical aperture in the frame. An end cover 117 closes the outer end of sleeve 116, this cover being bolted to the frame and normally preventing movement of the sleeve 116. At the opposite end of the roll, a retaining plate 118 is provided for preventing escape of the liner 114 from the aperture in the frame in which it is positioned.

For taking up end thrust, each of the rolls is

provided with a thrust bearing, and in the case of the carrier roll shown in Figure 6, this thrust bearing includes a thrust disc 119 secured upon the reduced terminal end portion 120 of the roll by means of a nut 121. Thrust washers 122 and 123 are positioned on opposite sides of the thrust disc 119, these thrust washers being free to rotate relatively to the disc, washer 122 fitting against the end cover 117 and washer 123 against the outer end of the liner 115. Ordinarily there is not very much end thrust upon the carrier rolls, but by the thrust bearing shown, any such end thrust is readily taken up while at the same time the roll is free to expand or contract lengthwise without crowding in its bearings. In removing the carrier roll, it will be understood that the coupling member 113 affixed to its left-hand end is first detached. Both carrier rolls 52 and 52' are similarly mounted and both are provided with thrust bearings and end covers as above described.

The top bending roll A is supported by means of underhung supporting caps 130, the edges of which are provided with flanges 130' which fit in grooves formed in the housing to receive them. The supporting cap 130 may be removed by moving it endwise outwardly after the end cover 131, which is bolted to the frame, is removed. After detachment of the coupling from the other end of this bending roll (which is done if the coupling is too large in diameter to pass through the available space between the cap and the lower rolls after they have been lowered), it may be lowered and removed from the machine, provided, of course, that the lower bending rolls B and C have first been lowered so as to permit the roll A to clear the machine. All three of the bending rolls A, B, and C are provided at their ends with thrust bearings substantially identical to that described in detail in connection with the carrier roll illustrated in Figure 6. The bottom bending rolls B and C have their ends mounted in the chucks 80 and 81, respectively, and may be readily removed from the machine after detachment of the couplings 113 affixed to the ends thereof respectively. It is not necessary in effecting removal of the bending rolls B and C to detach them from the chucks 80 and 81, but the rolls and chucks may be removed as units after the keeper plates 83 have been removed. The lower bending rolls, as well as the upper bending roll, are provided with thrust bearings.

In the operation of the machine the relative positions of the lower bending rolls with respect to the upper bending roll may be varied as desired to impart a greater or less curvature to the strips passing through the machine. In the bending of a strip it is caused to move around the upper bending roll with a radius of curvature sufficiently short to insure that at least a portion of the metal of which the strip is fabricated is stressed beyond its elastic limit. In this manner the strip is given a permanent set. The amount of permanent set given the strip may be controlled by regulating the relative positions of the three rolls, and without increasing the difficulty involved in passing the leading edge of a blank through the bending rolls.

Where both rolls B and C are mounted on the common support and are vertically adjusted simultaneously, a strip passing through is given a considerable reverse bend, as shown in Figure 10, whenever it is desired to impart a rather sharp curvature thereto. This causes the leading edge of each fresh strip to meet with difficulty in its initial passage through the rolls. Thus, as in

- dictated in dot and dash lines in Figure 10, it first strikes the upper roll considerably above its lowest point and is sharply deflected downwardly therefrom to impinge against the surface 5 of the second lower roll, as indicated in dotted lines. Where the strip is relatively stiff, great force must be exerted to overcome this resistance to entering, two sets of pinch rolls being sometimes required.
- 10 As indicated in Figures 11 and 12, however, the improved mounting for the lower rolls B and C permits the leading edge of an oncoming strip to pass freely between rolls A and C, no reverse bend in the strip being necessitated, and to strike roll B at a favorable angle. The amount of power necessary to force the strip through the rolls is thus minimized and the possibility that the leading edge of the strip be so far deflected that it will not pass between rolls A and B entirely 15 eliminated. It will be observed that, when the rolls are adjusted to the positions in which they are shown in Figure 12, it is possible to elevate roll B relatively to roll A, to a greater extent than is the case with the roll arrangement of Figure 20
- 25 11. Having thus described the invention, what is claimed as new and desired to be secured by Letters Patent is:
1. Strip coiling mechanism, including, in combination, three rollers, having parallel axes positioned to simultaneously act upon a strip passing between one of them and the other two, and means supporting said rollers whereby one of said last mentioned rollers may be bodily adjusted angularly of the first axis of the mentioned roller from one operative position to another without altering the position of the second of said last mentioned rollers and whereby the second of said last mentioned rollers may be individually adjusted relatively to the other two rollers.
2. Strip coiling mechanism including, in combination, three elongated rollers positioned to simultaneously engage a strip passing between one of them and the other two, and means for supporting said rollers for relative adjustment whereby the angles of entrance and delivery may be varied as desired without varying the angle of bend.
3. Strip coiling mechanism including, in combination, a fixed roller and two adjustable rollers, the fixed roller being positioned to engage one side and the adjustable rollers the other side of a strip, and supporting means for the adjustable rollers whereby one of said last mentioned rollers may be caused to approach or recede from the fixed roller or may be moved angularly relatively to the fixed roller.
4. Strip coiling mechanism including, in combination, a strip guide, a plurality of bending rolls positioned to receive and act upon a strip delivered by the guide, pinch rolls anterior to the bending rolls, a frame, and means carried by the frame for supporting the bending rolls and pinch rolls, said means permitting removal of the pinch and bending rolls from the path of strips delivered by the guide, thereby permitting passage of the work directly through the machine. 10
5. Strip coiling mechanism including mechanism for horizontally delivering strip, three horizontally disposed rollers, an upper roller and two lower rollers, for continuously acting upon and bending a strip as it passes from said mechanism 15 and between the upper roller and the two lower rollers, and means supporting said rollers, the upper roller being supported to rotate about a fixed axis and each of the lower rollers being horizontally and vertically adjustable relatively to 20 the upper roller.
6. Strip coiling mechanism comprising means for guiding a strip along a predetermined path, three rollers positioned adjacent the end of said guide means so as to act upon a strip issuing from said guide means and passing between one of them and the other two, the axes of said rollers being parallel and at least two of the rollers being supported so as to be adjustable at will in directions normal and parallel to the path of movement of the work to change as desired the relative positions of the rollers with respect to each other. 25
7. Strip coiling mechanism comprising means for guiding a strip along a predetermined path, three rollers positioned adjacent the end of said guide means so as to act upon a strip issuing from said guide means and passing between one of them and the other two, the axes of said rollers being parallel and the two last mentioned rollers 40 being supported so as to be adjustable in directions normal and parallel to the path of movement of the work to change as desired the relative positions of the rollers with respect to each other. 45
8. Strip coiling mechanism comprising means for guiding a strip along a predetermined path, three rollers positioned adjacent the delivery end of said guide means so as to act upon a strip issuing from said means and passing between one roller and the other two, the axes of said rollers being parallel and one of said last mentioned rollers being adjustably supported so that its axis 50 may be adjusted angularly about the axis of said first mentioned roller.
